US00D606063S

(12) **United States Design Patent**
Chen et al.

(10) **Patent No.:** US D606,063 S
(45) **Date of Patent:** ** Dec. 15, 2009

(54) **FRONT HOUSING FOR MOBILE DEVICE**

(75) Inventors: **Jung-pin Chen**, Kaohsiung Hsien (TW);
Shu-chen Lin, Kaohsiung Hsien (TW);
Shan-yao Chen, Kaohsiung Hsien (TW)

(73) Assignee: **King Slide Works Co., Ltd.**, Kaohsiung Hsien (TW)

(**) Term: **14 Years**

(21) Appl. No.: **29/339,182**

(22) Filed: **Jun. 25, 2009**

(51) **LOC (9) Cl.** **14-03**

(52) **U.S. Cl.** **D14/248**

(58) **Field of Classification Search** ..... D14/137, D14/138 R, 138 AA, 138 AB, 138 AD, 138 C, D14/138 G, 143-144, 147-148, 156, 218, D14/247-248, 341-347, 390, 399, 455-456, D14/496, 439; D16/208, 219; D21/329, D21/331, 333, 517; 348/14.01-14.02; 361/814; 379/433.01-433.13; 455/90.3, 556.1-556.2, 455/566, 575.1, 575.3, 575.4; D13/164, D13/168, 103, 119; 439/165; 343/702; 345/167, 345/168, 169; D10/65
